SCISSORS SHARPENER

George E. De Tray, Independence, Mo.

Application December 31, 1946, Serial No. 719,463

3 Claims. (Cl. 76—82.2)

1

This invention relates to sharpening devices for use in sharpening cutting tools. More specifically, the invention resides in the provision of a hand tool particularly designed to facilitate the sharpening of scissors.

The sharpener of the invention is in the form of a simply constructed and inexpensive device which may be employed for sharpening the cutting edges of the blades of a scissors without requiring any appreciable degree of skill on the part of the user.

The invention, together with its objects and advantages, will be best appreciated from the following detailed description read in reference to the accompanying drawing, in which is illustrated what is presently considered a preferred embodiment of the invention, and wherein;

Figure 1 is a plan view of a scissors sharpener embodying the features of the present invention;

Figure 2 is a side edge elevational view of the sharpener;

Figure 3 is a view similar to Figure 2, and illustrating an application of the invention, the blades of the scissors being shown in cross section; and

Figures 4 and 5 are cross-sectional views taken substantially on lines 4—4 and 5—5 respectively of Figure 1.

Referring now in detail to the drawings, the reference numeral 5 indicates generally a handle and shank assembly forming part of the sharpener. This assembly 5 is preferably formed from a single sheet of suitable material cut, shaped and dimensioned to provide relatively large end portions forming hand grips 6 and a relatively narrow intermediate connecting shank portion 7. At opposite edges of the shank portion 7 there are formed, integral therewith, angular tool guides 8. These guides 8 are disposed in the proximity of the points where the respective opposite ends of shank 7 merge with the grips 6. Further, and as shown, the guides 8 are laterally displaced with respect to one another as and for a purpose as will presently be made clear.

Also as an integral part of the structure, there are formed, as shown, clips 9 that extend inwardly from opposite edges of the handle assembly near the inner ends of the grips 6. These clips 9 function in a manner clearly shown to releasably retain in position an abrading element 10.

The free ends of the clips 9 are apertured to

register with apertures provided in the grip portion 6 for accommodating set screws 11. Obviously by tightening up on the set screws 11, the clips 9 are drawn into positive engagement with

5 the abrading element 10 for effectively securing the latter in the desired position.

In the present instance, the abrading element 10 is shown as being in the form of a cylindrical tempered piece of steel having on the periphery 10 thereof an abrasive or file cut surface.

The manner of using the sharpener to provide new cutting surfaces for the blades of a scissors is thought to be self-apparent upon reference to Figure 3. However, it may be briefly explained

15 that when so using the tool, the operator with one hand grasping a selected hand grip 6, positions the shank portion 7 of the tool between the blades 12 of the scissors. With the blades then

20 closed into contact with the periphery of the abrading element 10, the entire tool assembly is reciprocated relative to, and lengthwise of, the blades of the scissors. In connection with the foregoing, it will be noted that the guides 8 laterally engage the blades 12, and the abrading ele-

25 ment 10, being secured at the angle shown, contacts the beveled cutting edges of the blades 12 in complete conformity with the angle of the cutting edges. Thus, in using this device for

30 sharpening the scissors, the angle of the cutting edge of the blades of the scissors is maintained from heel to point of the respective blades with a resultant keen edge for the blades throughout their respective working or effective cutting edges.

35 As the working surface of the abrading element 10 becomes worn, or if for any reason another portion of the surface is desired, the screws 11 may be loosened after which the element 10 is then rotated about its longitudinal

40 axis or shifted in the direction of its length to bring a selected portion of its working surface into proper position with respect to the guides 8 for subsequent use. When the desired adjustment has been made, the screws 11 are then

45 tightened for securing the element 10 in the selected position of adjustment.

It will be further noted that the element 10 is positioned diagonally with respect to the longitudinal dimensions of the shank 7 and thus is

50 set on an angle substantially conforming to the

angle of the cutting edges of the scissors. This positioning of the abrading element is effected without requiring forethought on the part of the user, thus particularly adapting this tool to use by persons not especially skilled in the art of tool grinding or sharpening.

Although I have herein described a preferred form of the invention, I am aware that changes may be made within the scope of the claims hereto appended.

What I claim is:

1. A sharpener comprising a handle having a pair of hand grips and a narrow intermediate shank connecting said grips, tool guides at opposite edges of the shank and disposed laterally with respect to each other, and an abrasive element secured to the shank in a position diagonal with respect to the longitudinal dimensions of the shank and intermediate the tool guides.

2. A sharpener comprising a handle embodying a pair of end hand grips and an intermediate shank portion, tool guides at opposite edges of the shank and disposed laterally with respect to each other, clips mounted on said handle, and a file secured by the clips diagonally across the shank.

3. As a new article of manufacture, a tool handle formed from a single blank of material cut, shaped and dimensioned to provide as a unitary structure a pair of hand grips, tool-retention clips integral with the hand grips, a narrow intermediate shank connecting said hand grips, and diagonally opposed tool guides integral with said shank.
